UNITED STATES PATENT OFFICE.

JOHN DAMP, OF ASHLAND, OHIO.

GRAIN SEPARATOR AND SCOURER.

SPECIFICATION forming part of Letters Patent No. 311,727, dated February 3, 1885.

Application filed August 19, 1884. (No model.)

To all whom it may concern:

Be it known that I, JOHN DAMP, of Ashland, in the county of Ashland and State of Ohio, have invented new and useful Improvements in Grain Separators and Scourers, of which the following is a specification.

This invention relates more particularly to that class of separating-machines in which an inclined screen is employed in connection with an elevating mechanism, whereby the material which has passed over the screen is elevated and delivered on the top of the screen, and at the same time gradually moved across the screen, so that the material in passing from the inlet to the outlet side of the machine is repeatedly elevated and caused to flow over the inclined screen.

The object of my invention is to improve the construction of this class of machines, whereby the grain is freed from the dust, chaff, and other light impurities by means of air-currents passing through the machine, and to combine therewith a suitable scouring and cleaning device, whereby the wheat or other grain is thoroughly scoured and cleaned before leaving the machine.

My invention consists, to these ends, of the improvements in the construction of the machine, which will be hereinafter fully described, and pointed out in the claims.

In the accompanying drawings, consisting of four sheets, Figures 1 and 2 are end elevations of my improved machine. Fig. 3 is a vertical cross-section through the feed end of the machine. Fig. 4 is a horizontal cross-section of the machine in line $x-x$, Fig. 3. Fig. 5 is a vertical cross-section through the discharge end of the machine. Fig. 6 is a horizontal cross section in line $y-y$, Fig. 3. Fig. 7 is a side elevation of the machine. Fig. 8 is a perspective view on an enlarged scale of one of the scouring-plates. Fig. 9 is a fragmentary top plan view on an enlarged scale of the scouring mechanism.

Like letters of reference refer to like parts in the several figures.

A represents the frame or casing of the machine, composed of the upright posts a , horizontal cross-pieces a' , and suitable boards secured thereto, the whole forming a tight casing.

B represents the inclined screen covered with bolting or wire cloth, and arranged in the casing A and extending across the machine.

b represents inclined guide-boards or angle-

plates, arranged near the tail end of the screen and secured to a board, b' , extending across the tail of the screen. The guide-boards b are inclined in such a direction as to deflect the material toward the discharge side of the casing or machine, whereby the material is gradually moved from the receiving toward the discharge side of the casing.

C represents the elevating mechanism arranged in the casing A, with its ascending and descending sides on opposite sides of the inclined screen B. The elevating mechanism C consists of endless belts or chains c and buckets c' fastened thereto. The chains or belts c run around pulleys or sprocket-wheels c' , arranged in the corners of the casing, so that the ascending and descending sides and bottom portion of the elevator are parallel with the upright sides and bottom of the casing. The buckets c' of the elevator run close to the bottom of the casing, so as to pick up the material which falls on said bottom and elevate the same.

D represents a scouring-cylinder arranged below the tail end of the screen B, and rotating in a concave or semicircular trough, D' . The cylinder D is composed of circular plates d , which are each provided with a central hub or collar, d' , and are secured to a shaft, d'' , by set-screws d'' . The circular plates d are provided with grooves or corrugations d'' , which are arranged radially, or nearly so, as shown in Fig. 3. The corrugations d'' are arranged on both sides of the plates, and extend from the annular ribs d'' to the periphery of the plate. The trough D' is provided with sectional scouring-plates e , having radial corrugations or grooves e' on both sides, similar to the corrugations on the circular plates d . The plates e are semicircular in form, and rest with their outer peripheral edges in contact with the concave surface of the trough D' . The plates e are provided on their ends or corners with lugs or ears e'' , which rest upon the upper edges of the trough D' , and are secured to the trough by bolts or screws passing through the lugs e'' . The plates e are arranged transversely in the trough D' between the circular plates D , which latter revolve freely in the spaces between the plates e , as clearly shown in Figs. 4 and 9. The upper edges of the plates e are concaved, to allow the circular plates d , with their hubs d' , to extend in the trough between the plates e , so that the peripheral edges of

the circular plates will be close to the concave surface of the trough, and the corrugated faces of the plates *d* will be opposite the corrugations on the plates *e*.

5 *F* represents a brush-cylinder secured to a shaft, *f*, and arranged on one side of the scouring-cylinder *D* and parallel therewith. *F'* is a concave corrugated plate arranged below the brush *F* and in contact therewith. The 10 concave *F'* is preferably composed of a number of round rods or bars, *f'*, fastened at their ends to curved end plates, *f''*, which are secured to the casing of the machine. The upper edge of the concave *F'* is preferably connected to the upper edges of the concave trough *D'*, between the scouring-cylinder and the brush-cylinder, whereby the material as it escapes from the scouring-cylinder is caught by the brush and conveyed between the brush 15 and concave *F'*. The concave *F'* is connected at the discharge end of the machine with a discharge-spout *g*. The rods or bars *f'* are preferably indented or grooved on their upper surfaces, whereby the ends of the grains can 20 be acted upon by the brush *F*. The rods *f'* are arranged close together, so as to prevent the kernels of wheat from passing through them.

H represents a shaking-shoe arranged above 25 the casing of the machine and secured to the frame by spring-arms *h h*. The shoe *H* is provided with one or more screens, *h'*, whereby the grain is freed from sticks, straw, cockle, or other foreign matter, before entering the 30 machine.

I represents the feed-spout of the machine, which communicates at its upper end by a spout, *i*, with the shoe *H*, and at its lower end with an air-trunk, *J*, through which the 35 grain passes before it is delivered into the machine. From the air-trunk *J* the grain drops into the spout *j*, and through an opening, *j'*, in the casing onto the bottom of the machine. The air-trunk *J* extends upward 40 and across the machine, and is provided with a chess-hopper, *J'*, which communicates with the eye of a suction-fan, *K*.

L is a similar air-trunk arranged on the discharge end of the machine and communicating 45 at its lower open end with the discharge-spout *g*. The air-trunk *L* also extends upward and across the machine, and is provided with a similar chess-hopper, *L'*, which communicates with the eye of the fan 50 *K* on the opposite side of the fan-case *K'*. The air-trunks *J* and *L* are provided with suitable valves or dampers whereby the air-currents through the air-trunks are regulated and controlled.

55 *m* is an opening formed in the casing in rear of and below the head of the inclined screen, and *n* are openings formed in the top of the casing above the screen, and communicating with the eye of the fan by spouts *n'*. The 60 openings *n* are regulated or entirely closed by valves *n''*.

O is the driving-pulley, mounted on one end

of the shaft *f* of the brush-cylinder, motion being communicated to the pulley *O* by a suitable driving-belt.

70 *P* is a pulley mounted on the opposite end of the shaft *f*, and *P'* a similar pulley mounted on the shaft *d'* of the scouring-cylinder.

Q is an idler-pulley arranged above the pulleys *P P'*, and mounted on an arbor, *q*, secured to an upright standard, *R*, which is fastened to the cross-bars *a'* of the frame of the machine by bolts *r*. The standard *R* is provided with elongated openings or slots *r'*, through which the bolts *r* are inserted, and 80 whereby a vertical adjustment can be given to the idler-pulley when desired.

85 *S* represents an endless belt which runs over a pulley, *s*, mounted on the fan-shaft. The belt *S* runs from the pulley *s* down under the pulley *P*, thence over the idler-pulley *Q*, thence down under the pulley *P'*, and up to the pulley *s* on the fan-shaft, whereby motion is communicated from the brush-cylinder to the scouring-cylinder, and then to 90 the fan, and the brush and scouring cylinders are caused to revolve in the same direction.

95 *t* is a pulley mounted on the opposite end of the shaft *d'*, and *T* a pulley mounted on the arbor or shaft of one of the sprocket-wheels of the elevating mechanism.

T' is an endless belt running from the pulley *t* over the pulley *T*, whereby motion is communicated from the shaft *d'* to the pulley *T*, and thence to the elevating mechanism.

100 *u* is a pulley mounted on a shaft, *u'*, which is journaled in suitable bearings secured to the top of the machine.

u'' is a pulley mounted on one end of the fan-shaft, and *u'''* an endless belt running from the 105 pulley *u''* over the pulley *u*, and communicating motion to the shaft *u'*.

v represents a connecting-rod secured at one end to the shoe *H*, and its opposite end connected to an eccentric or cam mounted on the 110 shaft *u'*, whereby a reciprocating or vibratory movement is imparted to the shoe *H*.

115 The material to be separated is fed upon the shaking-shoe *H*, and any straw, sticks, or other foreign matter contained in the grain are separated therefrom by the riddle or screen *h'*, and the grain passes through the spout *i* into the feed-spout *I*. From the feed-spout *I* the grain enters the wind-trunk *J*, where the light grains or chess are caught by the air-current in the trunk *J*, and are carried upward in the air-trunk and deposited in the chess-hopper *J'*. The grain that drops out of the air-current falls onto the spout *j* and into the machine, and is carried upward by the elevating mechanism, and deposited upon the inclined screen *B*. From the screen *B* the grain falls into the scouring-trough *D'*, where it is subjected to a constant rubbing or scouring action between the corrugated surfaces of the 120 scouring-cylinder and trough. The material is then carried by the action of the scouring-cylinder to the outside of the trough, and caught up by the brush-cylinder and conveyed 125

by the action of the brush between the brush and the concave F', and deposited on the bottom of the machine. This operation is repeated a number of times as the material is gradually moved from the feed side to the discharge side of the machine by the angle-plates or inclined boards b. The material which has reached the discharge end of the machine is discharged from the brush-cylinder and concave upon the discharge-spout g, where it escapes into the air-trunk L, and the outer fiber of the grain and any other impurities contained in the grain which have been removed by the action of the scouring-cylinder and brush-cylinder are carried upward by the air-current in the trunk L and deposited in the hopper L'. The clean grain is discharged at the bottom of the air-trunk L. By means of the openings m in the casing, and the openings n, which communicate with the eye of the fan, a current of air is caused to circulate through the screen, and the grain, as it descends on the screen, is subjected to this air-current, whereby the grain is cooled and the fluff of the berry removed.

w represents a deflecting-board arranged near the head of the inclined screen, whereby the grain as it falls from the buckets c' is deflected on the head of the screen, and w' is a similar board arranged below the tail of the screen for guiding the material from the screen into the scouring-trough.

w" is a check-board arranged between the scouring-cylinder and the brush-cylinder, to receive the impact of the material as it escapes from the scouring-cylinder.

My improved machine is very simple and compact in construction, and forms a very complete and effective separating and scouring machine for cleaning wheat and other grain.

I claim as my invention —

1. The combination, in a grain separator, of an inclined screen, an elevating mechanism arranged with its descending and ascending sides on opposite sides of the inclined screen, a shaking-shoe which sifts the grain before entering the machine, and an air-trunk which receives the sifted grain from the shoe and effects a separation of the light grain and chaff from the heavy grain before it enters the machine, substantially as set forth.

2. The combination, with an inclined screen, of deflectors whereby the grain is moved laterally across the machine, a scouring-cylinder and concave which receive the grain from the screen, and an elevator whereby the grain is returned to the head of the screen after it has passed through the scourer, substantially as set forth.

3. The combination, with an inclined screen, of a scouring-cylinder and concave, whereby the grain is scoured after it leaves the screen,

a brush-cylinder and concave which receive the grain after it has passed through the scourer, and an elevator which returns the grain from the brush mechanism to the head of the screen, whereby the grain is repeatedly screened, scoured, and brushed in passing through the machine, substantially as set forth.

4. The combination, with an inclined screen, of deflectors whereby the grain is moved laterally across the machine, a scouring-cylinder and concave which receive the grain from the screen, an elevator whereby the grain is returned to the head of the screen after it has passed through the screen, and a separating air-trunk which receives the grain after the operations of screening and scouring are completed, substantially as set forth.

5. The combination, with an inclined screen, of a scouring-cylinder and concave receiving the grain from the screen, a brush-cylinder and concave receiving the grain from the scourer, an elevator whereby the grain is returned from the brush mechanism to the head of the screen, and a separating air-trunk to which the grain is finally discharged from the brush mechanism, substantially as set forth.

6. The combination, with the inclined screen, of a scouring-cylinder and concave receiving the grain from the screen, a brush-cylinder and concave receiving the grain from the scourer, an elevator whereby the grain is returned from the brush mechanism to the head of the screen, a separating air-trunk to which the grain is finally discharged from the brush mechanism, and a preliminary separating air-trunk through which the grain passes before it is subjected to the operations of screening, scouring, and brushing, substantially as set forth.

7. The combination, in a grain separator, of an inclined screen, B, an elevating mechanism, C, arranged with its ascending and descending sides on opposite sides of the screen, an inclosing-casing provided with air-inlet openings m in its side, and outlet-openings n in its top, and a fan, K, having its eye communicating with the openings n, whereby a current of air is drawn through the inclined screen, substantially as set forth.

8. The combination, in a grain-separator, of an inclosing-casing, an inclined screen, a concave arranged at the lower end of the screen and provided with scouring segments, a scouring-cylinder provided with scouring-disks working between the segments of the concave, and an elevator, substantially as set forth.

Witness my hand this 8th day of August, 1884.

JOHN DAMP.
